(Cl. 66—51)

This invention relates to knitting machines which are adapted to produce, inter alia, "flat" fabric which is fashioned to any desired formation. More particularly, the invention concerns the circular type of knitting machine which includes a needle cylinder, one or more banks of needles and relatively movable cams associated with said needles, said machine being adapted to produce hosiery blanks or other articles having areas fashioned in accordance with requirements.

In known types of "straight" or "flat" knitting machines which are capable of producing full fashioned hosiery in the "flat", the machine is adapted to form a panel which is located adjacent to the central seam at the back of the stocking, said seam being formed after the knitting operations have been completed. In this instance, the fashioning operation is effected by automatically decreasing at the selvage edge or edges the number of needles employed, and also doubling by means of stitch transfer mechanism one or more stitches at a relatively short distance from the selvage edge at that section of the hose which is being fashioned.

Hitherto, circular knitting machines of a known type have been adapted to produce a certain type of full fashioned hosiery, and, for this purpose, a portion of the knitting mechanism of the machine, such as the needle cams, was adapted to oscillate whilst the whole of the hose was being knitted with the exception of that section or sections knitted on the full number of needles, in which case the machine was adapted to perform a full rotary knitting operation giving a tubular fabric. The section of the hosiery to be fashioned was formed by causing the needle cams, for instance, to oscillate temporarily, whereby this particular section of the hosiery was knitted in the "flat", the number of needles employed being increased until the maximum diameter of the hosiery had been reached, whereupon the rotary knitting operations were resumed to complete the hosiery.

The aforesaid type of circular knitting machine has not proved to be satisfactory in practice for fashioning purposes, in that the oscillating movements of a portion of the knitting mechanism retard the speed of the machine and thus decrease its output. Furthermore, it is not possible on such a machine to produce ordinary full fashioned hosiery, namely, hosiery including a panel as aforesaid, for the reason that this circular type of knitting machine functions to add one or more needles at the selvage edge

on each change in width, thus producing a fabric in which the wales converge into the selvage and a panel as aforesaid is not produced. On the other hand, the straight or flat type of knitting machine which is adapted to produce ordinary full fashioned hosiery as aforesaid normally operates at a relatively slow speed so that these machines are not only expensive as regards their initial cost but have a relatively low output which seriously affects the cost of the finished product. In addition, it is well known that the latter type of machine is of such a nature that it is usually necessary to maintain a constant temperature and humidity in the room in which the machine is operating and, in having to work in such a temperature, the general health of the operatives is frequently impaired. Circular machines are not subject to these handicaps.

It has also been known to knit two blanks in a rotary manner while reciprocating a separate yarn guide for each blank, but these have not been satisfactory and no way has heretofore been known to fashion the blanks to duplicate the ordinary full fashioned stocking blank.

The primary object of the present invention is to provide an improved circular knitting machine of the type referred to which is adapted to produce fashioned fabric such as full fashioned hosiery having a panel as aforesaid, the entire fabric being knit whilst the knitting elements of the machine are being operated in a rotary direction, thus eliminating the undesirable oscillating movement of the camming elements and considerably increasing the effective speed of the machine. The improved circular machine is adapted to produce full fashioned hosiery which is substantially identical with hosiery produced by the aforesaid flat or straight type of machine, the improved machine being adapted to transfer stitches during the formation of the panel and other fashioned areas of the stocking and to decrease the number of needles employed at these zones in a manner similar to the functioning of the flat machine.

The initial cost of the improved circular machine is considerably less than the cost of the flat or straight type of machine, as aforesaid, whilst in addition the improved machine is of simpler construction and is adapted to operate at a much greater knitting speed than the aforesaid known types of circular or flat machines, thus considerably increasing the rate and consequently lowering the cost of production.

Various other objects and features of the invention will be more readily apparent from the

following description which refers, by way of example, to one practical embodiment of the invention. In this embodiment the needles are independent latch needles and the needle cylinder is stationary but it should be understood that the invention is not confined to this type of machine. The invention is applicable to latch needles or bearded needles, independent or united.

In the drawings,

10 Fig. 1 is a front view in elevation of the head and bedplate of a circular machine constructed in accordance with my invention, some of the parts being omitted for clarity;

15 Fig. 2 is a plan view of the head of the machine taken just below the means for tipping the combs, showing the mechanism for shogging the combs and moving them vertically, and the mechanism for retiring the sinkers prior to transfer;

20 Fig. 3 is a plan view of the machine taken just above the upper bedplate on line 3—3 of Fig. 4, showing the upper cam block, the narrowing jaws and the fashioning cams;

25 Fig. 4 is a view in elevation from the rear of the machine, showing the racks and pawls for shogging the jaws and combs;

30 Fig. 5 is a condensed view in sectional elevation through the top of the needle cylinder, showing the yarn carriers and sinkers and their control and driving means, taken on the line 5—5 of Fig. 6;

Fig. 6 is a condensed plan view corresponding to Fig. 5, showing the yarn carriers and associated parts;

35 Fig. 7 is a vertical section through a cam block;

Fig. 8 is a view in elevation of the outer end of a cam block;

Fig. 9 is a view in elevation of the saddle controlling vertical movement of a jaw unit;

40 Fig. 10 is a vertical view, partly in section, of the mounting of a comb, taken on the lines 10—10 of Fig. 12 and 10—10 of Fig. 11;

45 Fig. 11 is a view in elevation looking radially inward at the machine, taken on the line 11—11 of Fig. 10, showing the comb and how it is mounted;

50 Fig. 12 is a plan view from the top of the machine showing the bracket joining the upper ends of the bedplate posts and some of the mechanism for moving the narrowing points radially;

55 Fig. 13 is a view in elevation from the right side of the machine, and Fig. 15 a plan view, of the unitary cam means controlling the rotary knitting clutch and the reciprocating yarn finger clutch;

Fig. 14 is a detail view in side elevation of the means driving the heart-shaped cam;

60 Fig. 16 is a vertical view in section through the main countershaft, taken on the line 16—16 of Fig. 15, showing the driving connections from the countershaft;

65 Fig. 17 is a view in elevation from the right side of the machine, showing how the reciprocating motion for the yarn carriers is obtained from the heart-shaped cam;

70 Figs. 18 to 24 are side elevations of the fashioning cams and levers on one of the fashioning cam shafts; Fig. 18 showing a cam to give the radial or tipping movement to a narrowing comb;

Fig. 19 a cam to give radial movement to a jaw unit; Fig. 20 a cam to give vertical movement to a jaw unit; Fig. 21 a cam to give vertical movement to a comb; Fig. 22 a cam to shog a jaw unit circumferentially; Fig. 23 a cam to cause with-

drawal of the sinkers during transfer; and Fig. 24 a cam to shog a comb circumferentially;

Fig. 25 is a view in vertical section through the means for shogging the combs, taken on the line 25—25 of Fig. 2;

5 Figs. 26 to 35 are diagrammatic illustrations of the manipulations of the jaws, needles and combs at various stages in the narrowing process to produce the panel;

Fig. 26 shows in solid lines the retracted or idle 10 position of a jaw unit 100L, and in dotted lines, the position of the jaw unit in engagement with the needle jacks preparatory to beginning transfer of loops;

Fig. 27 is a view similar to Fig. 26 showing the 15 needles raised to a clearing level and the points lowered sufficiently to engage the needle hooks;

Fig. 28 is a face view of a needle, needle loop 20 and point showing their relation when in the position of Fig. 27;

Fig. 29 is a view similar to Figs. 26 and 27 showing the needles down momentarily out of action with the stitches on the points and the latter swung radially out of the path of the needles;

Fig. 30 is a view showing the upper part of Fig. 29 with the points raised a little from their position of Fig. 29 to clear the sinkers and the points about ready to be shogged;

Fig. 31 is a plan view of the upper and lower 30 jaws of a jaw unit 100L after being shogged to the right two needles while still in the down position of Fig. 29;

Fig. 32 is a detail view in elevation of the relation of the jack butts to the jaws and lug on the 35 upper jaw while in the position of Fig. 31;

Fig. 33 is a view similar to Figs. 26, 27 and 29, showing the new selection of needles raised to an intermediate level preparatory to receiving the transfer loops, the dotted position showing the 40 points when swung back against the needles to return the loops to the needles;

Fig. 34 is a detail of the upper part of Fig. 33 showing the points and needles moved further together vertically than in the position in Fig. 45 33 with the loops on the needles;

Fig. 35 is a detail in radial elevation similar to Fig. 28, of a needle and point, showing the position of the loop as the needle and point start to separate; while

50 Fig. 36 is a diagrammatic view in elevation of the gears driving the cam blocks carrying the rings.

The improved knitting machine has a main bedplate 25 supported upon a main frame 26. 55 Mounted upon this bedplate is a main drive shaft 27 adapted to be driven from any convenient source of power by pulleys 28, 29. To drive the machine this main shaft 27 can be connected to a train of gears 30, 31, 32 or any other suitable 60 transmission mechanism. The driven gear 32 is mounted loosely on a countershaft 33 and there is a clutch face 34 on one side of the gear. Adapted to engage this clutch face is a slide 35 also having a clutch face but keyed on the 65 countershaft 33, these two clutch faces forming the main clutch unit. When the face and slide are in engagement the countershaft revolves with the main shaft. The countershaft extends inwardly to a point below a stationary needle cylinder 36 on the main bedplate. The countershaft drives a revolving lower cam block 41 by means of a main bevel gear 37 meshing into a horizontal bevel gear 38 resting on the bedplate and a spur gear ring 39 fastened on the upper face of the 70 75

bevel gear. The cam block 41 is mounted on a sectional carrier plate 40L screwed on top of the spur gear ring. The block is free to slide radially on the plate. Extending upwardly from the main bedplate are posts 42. A short distance above the main bedplate on these posts is an upper bedplate 43 carrying an upper cam block 44. This cam block is mounted on a carrier plate 40U like the lower one and can slide radially toward and away from the cylinder. The plate 40U is screwed on top of another spur gear ring 39 turning on a block sitting in the upper bedplate.

When the countershaft 33 turns clockwise as viewed from the right side of the machine (Fig. 13), the lower cam block 41 turns counterclockwise as viewed from above, but the upper cam block 44 turns clockwise. To drive the upper block in this manner there is an operative connection from the lower spur gear 39 comprising the following elements. Meshing with the lower spur gear 39 is a gear wheel 45 tight on a vertical shaft 46 extending upwardly to a point beside the upper bedplate 43 (Figs. 3 and 36). On the upper end of the shaft 46 is a wheel 47 meshing with an idler gear wheel 48 which in turn drives the upper spur gear ring 39 in a direction opposite to the lower spur gear ring.

The needle cylinder 36 has the usual open radial slots 49 running longitudinally on its periphery and in these slots are located the usual needles 50. These needles may have extensions or tails which carry the necessary operating butts, but preferably the operating butts are on attached jacks 51, as shown in Figs. 26 and 27. The upper end of each jack may be provided with a hook or pocket adapted to accommodate a complementary projection upon the lower end of its needle whereupon the jacks may be employed for imparting both an upward as well as a downward movement to the needles. In the drawings there is an upper operating butt 52 and a lower operating butt 53—one for each cam block. In any case each needle customarily has a plurality of operating butts associated with it. There is a group of needles in the cylinder for each stocking blank to be knit and there is a gap or space between the ends of the groups. In the example shown in the drawings there are two groups of needles.

The knitting cam blocks 41, 44 are of identical construction but arranged in a reverse manner so as to engage their associated needle butts whilst moving in opposite directions. Each cam block may include the cams necessary to produce a knitting wave and arranged so as to form an open-ended cam groove therebetween which is adapted to accommodate the butts of the needles or needle jacks. In addition, each cam block may include means for effecting radial movement of its cams in relation to the needle cylinder, whereby the aforesaid cam groove may be adapted to operate needle butts of different lengths selectively. This manipulation is used in the manufacture of heel tabs, as will be described later. The movement can be controlled from the main pattern drum of the machine (not shown) by any convenient system of cams and levers which can place a lug 199 or striker for star wheel 54 in the path of the rear end of the cam block. This lug or striker when pushed radially inward will operate a star wheel 54 on the carrier plate 40 opposite the cam block (see Figs. 7 and 8). On a pin 55 projecting upwardly through the cam block and carrying the star wheel 54 is a cam wheel 56 with alternate high

and low levels. These surfaces engage in turn against a small upstanding lug 57 on the cam block radially outside the pin 55. There are springs 58 tending to pull the cam block radially inward. When a low surface on the cam wheel 56 is opposite the lug 57, the block is in position to engage both long and short butts. When a high surface engages the lug the block is partially withdrawn till the cams are in the path of only the long butts.

Located above the cam blocks upon the supporting posts and adjacent to the top of the needle cylinder are two yarn carriers 73, 74 each mounted upon one of a pair of concentric rings 71, 72 in a circumferential guideway 75 (see Fig. 15). Each of these yarn carriers performs oscillating movements with relation to one group of needles, i. e., there is a separate yarn carrier for each stocking blank. Each yarn carrier has one or more yarn fingers 83 and a support 84 therefor mounted on one of the aforesaid circumferential rings.

In the embodiment shown in the drawings the oscillating movement of the yarn carrier is obtained from the countershaft 33 by means of a heart-shaped cam 59. On the countershaft 33 is a small pinion 60 meshing with a larger gear 61 which in turn engages a small pinion 62 revolving one to one with the countershaft 33 and cam blocks 41, 44 (see Fig. 14). This second pinion 62 turns a shaft 63 carrying the heart-shaped cam 59. This heart-shaped cam is a double path cam and moves a roller 64 on one arm of a bell crank lever 65 (see Fig. 17). The end of the other arm of the lever is a gear segment or quadrant 66 meshing with a pinion 67 turning freely on the countershaft 33. Attached to one side of this free pinion is a bevel gear wheel 68 which also meshes with a bevel pinion 69 on the lower end of a vertical drive shaft 70 (see Fig. 16). This shaft extends upwardly through the main bedplate 25 to the level of the rings 71, 72 which carry the yarn carriers 73, 74.

On the upper end of this vertical yarn finger drive shaft 70 is a horizontal gear 76 which acting through an opening in the circumference of the guideway 75, meshes with teeth 77 on the periphery of the outer yarn carrier ring 71 (see Fig. 5). Just below this gear 76 on the shaft 70 is a bevel gear 78 meshing with a bevel pinion 79 on a short shaft 80 extending under the outer ring 71, through bevel gear 81 onto teeth 82 on the inner ring 72 and driving same in a direction reverse to that of the outer ring. Each carrier oscillates over the full width of its group of needles in a direction opposite to that of the other carrier.

On the top of the needle cylinder 36 is any usual form of outside sinker ring 144, the sinkers 85 moving radially in slots in the outside ring 60 and the inside sinker ring 86. To actuate the sinkers of each bank of needles there is a movable cam plate 87 guided by a sinker cap 142 and driven by a pin 88 upstanding from the cam plate through a slot in the cap. This pin is actuated by its yarn carrier. In view of the fact that the sinker cams must lag behind the yarn finger first on one side and then, on the return movement of the carrier, on the other, the driving pin 88 takes into a slot in the yarn carrier 73 or 74 so that the cam changes position automatically when the carrier starts in a new direction.

It will be observed that with this machine the fabrics produced have selvage edges down each side of the blank. If necessary any of the usual

precautions to avoid tight stitches at the selvage can be taken, such for instance as laying the yarn around the last needle but not knitting thereon by means of picker manipulation.

5 In making heel tabs, it is necessary to make one heel tab on one end of a bank of needles with one yarn and the other heel tab on the other end of the bank of needles with another yarn. For this purpose there are two yarn fingers 83 in each carrier, i. e., for each bank, and during the making of heel tabs these fingers are moved into and out of feeding position in alternation. As shown in Figs. 5 and 6, the fingers swing upwardly and inwardly when going out of action. 10 To raise a finger pressure is applied just below the pivot point by a slide 89 horizontally mounted in the carrier, there being two slides in each carrier, one for each finger. These slides are actuated in alternation by a pair of rotating cam wheels 90 mounted on a vertical pin 91 extending downward through the carrier. On the lower end of this pin is a two-stud trip lever 92. A stationary lug 93 on the guideway at each side of the machine protrudes into the path of the stud or arms of each lever 92. When a carrier oscillates in one direction its lug 93 turns its lever 92 in one direction, and on a swing of the carrier in the other direction the lug hits the other arm of the lever 92 and turns the pin 91 in the other direction. These oscillatory movements of the pin move the cam wheels enough to actuate the slides and fingers in alternation. The lug is so located that the changes occur while the fingers are midway between the heel tabs. The lug can be moved into and out of operative position by lever connections 94, 95 from the main pattern drum. An inoperative position can be obtained by a mere raising of the lug above the level of the trip lever 92.

40 In combination with the foregoing, the improved machine includes means for fashioning the hosiery or other fabric being produced, said fashioning means being adapted to reduce the effective number of needles employed at the selvage edges of the fabric and a panel similar to the panel present in the fabric produced upon a flat or straight type of full fashioned machine is formed in the hose or the like, as hereinafter described. Said fashioning means include stitch transferring mechanism incorporating a second clutch device.

55 Mounted upon the bedplate adjacent to each side of the needle cylinder is a fashion cam shaft 96 which is operable from the main driving shaft and adapted to cooperate, for instance, with a plurality of cams, links and levers to actuate the improved fashioning mechanism hereinafter described. The second clutch device may be mounted on this fashion cam shaft. This clutch 97 drives the fashion cam shaft. The two shafts 96 are connected by two pairs of bevel gears 98 and a cross shaft 99 at the back of the machine (Fig. 4).

65 65 The driving connection between the counter-shaft 33 and the first fashion cam shaft 96 is shown in Figs. 13, 15 and 16 and comprises a bevel gear 101 on the side of the driven gear 32 on the countershaft which meshes with a bevel pinion 102. This latter pinion is on the lower end of a vertical shaft 103 supported on the main bedplate 25. On the upper end of this shaft is another bevel pinion 104 meshing with a bevel gear 105 mounted on one end of a short horizontal shaft also carried by the bedplate. On

the other end of this horizontal shaft is a small gear wheel 106 meshing with a larger gear wheel 107 turning freely on the adjacent fashion cam shaft 96. The free member of the fashion cam shaft clutch 97 is fixed to this large gear wheel 107 while the other clutch member is slidably keyed on the shaft.

10 In order to operate this clutch in proper timed relation to the main or knitting clutch, the two are linked together as follows. The necessary longitudinal movement of the keyed member of the fashion clutch is obtained from a horizontal lever 108 pivoted on the housing of the shaft carrying the gears 105 and 106. The other end 15 of the lever 108 is linked to one arm 109 of a three-arm bell crank lever pivoted at the juncture of the arms. Actually, in the embodiment shown in the drawings, the lever 109 is above the other two arms and is mounted on the upper end of a 20 vertical shaft 111. This shaft is carried by the main frame 26. A second arm 110 of the bell crank is lower down on the shaft and has a jaw taking into the sliding or keyed member of the main or knitting clutch, while the third arm 112 25 actuates the other two arms. The end of this operating arm carries a roller lying in a cam path 113 of a shipper drum 114 which is racked around by a rack wheel 115 controlled from the main pattern chain (not shown). The parts are so adjusted that one clutch is always in engagement, the two clutches working in alternation.

30 Means are provided for preselecting a section of each bank of needles employed in forming the fabrics and manipulating such plurality of needles in unison to transfer the needle loops 200 to other needles for the purpose of fashioning the fabric and producing the panel as aforesaid. A section at each end of each bank is thus treated. Thus the machine in the drawings has four jaw 40 units (see Fig. 3). Said needle selecting mechanism may include one or more jaw units 100R, 100L, each comprising a pair of pivoted jaws 116, 118 or 117, 118 adapted to be operated by linkage 45 engaging one or more cams on the fashion cam shafts 96.

45 Each of the aforesaid jaw units is universally mounted on the upper bedplate 43, the upper jaw 116, 117 in each case being preferably influenced by a spring 119 and capable of lateral movement in relation to its lower jaw 118. The upper jaws 116 in the units 100R can move laterally clockwise, while the upper jaws 117 in the units 100L can move laterally counterclockwise. The upper jaws are also provided with an elongated upstanding extension or lug 120 adapted to bear against the side of one of the needle butts when the jaw is depressed (Fig. 29) so that, during bodily movement of the jaw unit in a direction circumferentially of the needle cylinder, the extension or lug engages the next adjacent needle butt of the remaining needles or jacks in the bank, and thus retards further movement of the upper jaw whilst the lower jaw continues to move beyond the end of the upper jaw (Figs. 31 and 32). By virtue of this pushing aside of the upper jaw a portion of the lower jaw is thus automatically positioned beneath one or more predetermined needles of the remaining needles in the bank. Whilst the associated upper and lower jaws occupy these particular relative positions, an upward movement is imparted to the jaw unit whereupon the aforesaid predetermined needles are engaged by the end of the lower jaw and a corresponding number of needles 55 60 65 70 75 80 85 90 95 100 105 110 115 120 125 130 135 140 145 150 155 160 165 170 175 180 185 190 195 200 205 210 215 220 225 230 235 released at the opposite end of the jaw unit, namely, at the selvage edge. Continued upward movement of the jaw unit causes the upper jaw to clear the adjacent needle butts, whereupon the 5 spring 119 functions to return the upper jaw to its original position automatically. The jaw unit now has hold of a new selection of needle jacks—it has been shogged.

In order to perform all their functions, each 10 jaw unit must swing counterclockwise and clockwise and up and down and also be able to move radially toward and from the needle cylinder. The mounting comprises a block 121 on the upper bedplate carrying a dovetail-shaped horizontal slot in which a slide 122 is adapted to move circumferentially. This allows the counterclockwise and clockwise movements of the jaw unit. On the upper edge of the slide is a hollow block 123 through which the arm 124 of the jaw unit 15 slides. The sides of the hollow block are slotted at 125 and those holes carry a pin 126 which goes through the arm. These slots are spaced from the bottom of the hollow portion and the arm can be swung up and down. Because of the 20 slots 125 the arm can be moved toward and away from the cylinder to get it into and out of operative position.

All the movements of the jaw units are obtained from the fashion cam shafts 96. I will 30 describe the operative connections for the unit at the right front of the machine. Mounted on the fashion cam shaft is a double track cam wheel 127 with a cam lever 128 pivoted on a rock shaft 129 and carrying a roller resting on the 35 cam wheel. The free end of the cam lever is connected by a link 130 to a bell crank 131 pivoted on the guideway 75. The free end of the bell crank surrounds a lateral extension of the pin 126 of the jaw unit but allows circumferential movement of the pin with the jaw unit. 40 Rotation of the fashion cam shaft causes the rocking of the bell crank and therefore radial movement of the pin and jaw unit. The up and down movement of the jaw unit is obtained from a double track cam wheel 132 on the fashion cam shaft. This wheel has a cam lever 133 pivoted on the rock shaft 129 with the usual roller. The 45 free end of this cam lever is connected to the lower end of a vertical slide 134 carried in a slide block 135 on the main bedplate. The upper end of this slide is shaped to form a horizontal saddle 136 which surrounds the outer end of the jaw arm 124. This saddle allows for the circumferential movement of the jaw unit. Rotation 50 of the cam shaft causes the slide 134 to move up and down carrying the jaw arm with it, upward movement of the slide lowering the operative end of the jaw unit.

The circumferential movement of the jaws is 60 obtained as follows. Mounted on the under side of the upper bedplate 43 are two large disks 173, 174, one below the other (Figs. 1 and 4). A bracket 143 is attached to the upper disk 173 and it extends upwards and outwards around the 65 bedplate and is connected to the slide 122. On the periphery of this upper disk at the back of the machine is a toothed segment 137. Acting upon this toothed segment is a racking pawl 138 attached pivotally to a cam lever 139 vertically 70 mounted on the main bedplate. This cam lever carries a roller bearing against a cam wheel 140 on the fashion cam shaft. The cam lever is held against the cam wheel by a tension spring 141. Rotation of the fashion cam shaft causes the 75 racking pawl to rack the upper ring one tooth

counterclockwise, carrying the jaw unit with it towards the center of its bank of needles. This movement may be over one or more needles. In the drawings I have shown it equal to two needles. In a two-blank machine the jaw unit 5 diametrically opposite on the other bank of needles is also connected to the upper ring. The ring movement described therefore also moves that jaw unit toward the center of its own needle bank. The other two jaw units are similarly 10 mounted on the lower ring; this ring receiving its circumferential movement in a like manner but in a clockwise direction. At the completion of the blanks, these units can be returned to their original position by any suitable similar racking 15 mechanism.

Cooperating with the needle selecting mechanism is a series of transfer points which may be of known type and of substantially inverted U shape in horizontal cross-section, said transfer points being mounted upon the supporting frame and adapted to be moved towards and away from the needles by any suitable means, such as a system of links and levers operatively connected to the cams on the fashion cam shaft. 20 The U-shaped transfer point above referred to is more particularly suited for a bearded needle machine. For a latch needle machine I prefer to use a split point composed of two spring blades for each point, the hook of the needle passing 25 between the two blades.

In order to perform all its necessary functions, the transfer comb 145 or points must be able to move up and down, circumferentially and radially to and from the needles. In the drawings the controls are shown in Figs. 10, 11, 12, 25, 30 1 and 2. The combs are mounted above the needle cylinder on two pairs of comb-carrying arms 146, 147 which are carried on a stationary spindle 148. This in turn is supported by a bracket 35 149 on the upper ends of the posts 42. The narrowing points 150 hang vertically above the needles. In a similar manner to the jaw mountings, the two diametrically opposed combs are mounted on an upper pair of arms 146 and the 40 other two on a lower pair of arms 147. These are revoluble on the spindle 148. The points are conveniently carried in a slotted block 151, each pair of blades being the same distance apart as the needles. The block is mounted on a horizontal pivot 152 resting in a vertical slide 153 in the end of each arm, which is formed as a vertical guide, said slide being carried on the ring. The front right comb is on one of the upper arms 45 146. There is a jaw unit for each comb.

The movements of the comb are all obtained from the fashion cam shaft. Mounted on this shaft is a cam wheel 154. A cam lever 155 for same is located on the rock shaft 129 and its free end is connected by a link 156 to a horizontal 60 arm 157 pivoted on a bracket on one of the posts 42. The cam lever is held in contact with its cam wheel by a tension spring 163. The inner end of the horizontal arm 157 carries a cross member 158 which bears on a stud 159 on the 65 upper side of a horizontal saddle 162. Also carried on this arm 157 is a pivoted member 160 held up by spring 161 on the arm 157. This pivoted member reaches into the horizontal saddle 162. The horizontal arm and the pivoted member grip the saddle 162 between them and control the vertical movement of the slide 153 and comb 145. Rotation of the fashion cam shaft through its linkage 155, 156, 157 causes vertical 70 movements of the saddle 162 and its points 150. 75

The radial movement of the comb comes from a cam wheel 164 on the shaft 96 and cam lever 165. The free end of the cam lever 165 is connected by a link 166 to an arm 167 pivoted on a bracket 168 on the horizontal bar 196 carried by the posts 42. On the upper end of the spindle is a four-arm bracket carrying guides 204. Each guide contains a vertical slide 169 attached at its upper end to the pivoted arm 167. The lower end of this slide carries a cross member 170 resting against which is a thrust bar 171 vertically mounted on the upper end of the transfer point block 151. This thrust bar is held in contact with the cross member by a spring (not shown).

15 The thrust bars being mounted on the blocks 151 are shogged with their combs and therefore move circumferentially with relation to the cross members 170. (The direction of movement of the combs when narrowing is indicated by the arrows in Fig. 2.) Owing to the contour of the thrust bar, any vertical movement of the point block 151 or the slide 169 alone will cause the point block to be rocked on the pivot 152. This rocking motion imparts the radial movement 20 of the points to and from the needles. If the comb and cross member move vertically in unison, no radial movement is imparted to the points. The rotation of the fashion cam shaft 96 causes the rock lever 165 through its link 166 to turn the 30 inner end of the pivoted arm 167 downwardly and also the vertical slide 169 and its cross member 170 (see Fig. 10). In the absence of a rocking motion imparted by relative movement between the slide 169 and the thrust bar 171, a tension spring 205 between the horizontal arm 157 and the slotted block 151 keeps the points in vertical position.

40 Mounted on each of the comb-carrying arms 146, 147 is an arm 175 which contacts with a slide 176 at the rear of the machine. Both slides are mounted in a horizontally dove-tailed block 177 (Figs. 4 and 25). On each slide is mounted a toothed segment 178 which is acted upon by opposed racking pawls 179. The racking pawls 45 are connected to the free ends of cam levers 182 vertically mounted on the bedplate. This cam lever is operated by a cam 183 on the fashion cam shaft 96. The circumferential travel of the blocks 176 and toothed segments 178 is limited by stops 206, 207 on the circumference of the upper guideway 75. The lever 182 carries a roller and a tension spring 184 as in the case of the levers 155 and 165, and rotation of the cam shaft 96 causes the cam lever 182 to move 50 the sliding block through its racking pawl 179. The sliding block carries the arm 175 circumferentially and so shogs the points. For the purpose of accurately locating the points above the needles, there is a micrometer adjusting screw 202 mounted on the end of the arm 175 which contacts the upper block 176 (Figs. 2 and 4). A tension spring 203 keeps the micrometer screw and block in contact. There is a similar device for the lower arm 175.

60 Rotation of the fashion cam shafts results in each jaw unit selecting a predetermined number of needles in the bank and raising them towards the transfer points which are simultaneously caused to descend into engagement with the needle heads (Figs. 27 and 28). Following upon such engagement, the transfer points and needles are caused to descend bodily until the needle heads have reached a position below the normal knitting level. During such downward movement, the loops 200 normally carried by the 70

needle heads are transferred onto the points consequent upon the needle heads and points while still in engagement with each other, being drawn through the stitch loops (see Fig. 29).

75 The points have now reached the limit of their downward movement and are subsequently raised to a position immediately below the heads of the remaining needles in the bank, the stitches being retained upon the transfer points during this movement.

10 The needles continue their downward movement until they have reached the limit of their descent, namely, an idle or non-knitting position (Fig. 29).

15 At this juncture, the needle selecting mechanism, namely, the jaw units, have a movement circumferentially of the needle cylinder imparted thereto, whilst in addition relative endwise movement occurs between the upper and lower jaws of each unit, thereby disengaging the jaws from one or more needles at the end of the bank, namely, at the selvage edge, and positioning upon the projecting portion of the lower jaw, a corresponding number of adjacent needles in the bank (Figs. 31, 32). The selvage edge needles disengaged from the jaws are in non-knitting position (Fig. 29). Whilst this movement of the jaws is taking place, the transfer points receive a lateral movement sufficient to position them clear of the needle heads (Fig. 30).

20 A circumferential movement similar to that given to the jaw units is now imparted to the transfer points carrying the stitches, whereby they are positioned above the needle under which the lower jaw is already located.

25 The jaws are now adapted to raise the new series of preselected needles to a position preparatory to having the stitches returned to them from the transfer points. When in this position the needle heads are located immediately under the 30 stitches held by the points (Fig. 33). The latter receive a return lateral movement for the purpose of effecting a reengagement between the points and the needle heads. The transfer points descend for a relatively short distance and the 35 needles ascend for a similar distance, thereby transferring the stitches back to the needles. A slight lateral movement is then imparted to the transfer points for the purpose of moving them towards the centre of the needle cylinder, thus 40 exposing the needle heads so that further upward movement of the points effects the release of the stitches from the points onto the needles (Figs. 34, 35). The transfer points are then 45 returned to their original position.

50 Each of the jaw units is now retracted clear of its associated needle butts, the fashion cam shaft declutched and the main clutch engaged, whereupon the normal knitting operations are resumed.

55 In order that loops may be removed from needles or returned during narrowing, it is necessary to withdraw the nibs of the sinkers 85. This also can be accomplished from the fashion cam shaft. One means of carrying this out would be to have depending butts 186 on the outer ends of 60 sinkers in the fashioning area. In the drawings a ring 187 is placed underneath the sinkers to which ring are attached cams 188 adapted to retract sinkers having depending tails (Fig. 5). When not fashioning, these cams lie in the spaces 65 between the banks of needles and in the center non-fashioning areas. When fashioning, the ring carrying the cams is turned circumferentially till the cams retract the appropriate sinkers. When 70 the fashioning is over, the ring is moved back 75

and the regular sinker operating cams take control of the sinkers again to return them to their inward position. For this purpose there is another cam wheel 189 on the fashion cam shaft, a vertical bent cam lever 190 and tension spring 191 which is connected to a bell crank lever 192 through a link 193, the bell crank lever being pivoted on the guideway 75 for the yarn carrier rings (Figs. 2, 4 and 25). The free end of the bell 10 crank lever is connected by a link 194 to the cam ring 187. An alternative method would be to introduce a cam on the sinker cam plate into the path of the sinker butts at the rear of the sinker wave, so that as the course prior to a fashioning 15 operation is being knitted, this cam will sweep all sinkers outwardly to free the nibs of loops and leave them well clear of the needles. The continued knitting operation returns the sinkers to their inward position.

20 The usual spring takeup mechanism is provided to take up the slack yarn, when the yarn carriers change their direction of rotation.

During the fashioning operation a predetermined number of stitches such as fifteen, more 25 or less, have been removed from their respective needles and moved circumferentially say two needles, so that the sixteenth and seventeenth needles, not having had their stitches removed, have an extra stitch placed thereon when the 30 transfer points return the stitches to the needles. This doubling of stitches at regular intervals introduces a distinct series of marks in the fabric, into which some of the wales outside the said 35 series of marks converge at an angle, whilst all wales inside said marks remain vertical, thus producing a panel effect as aforesaid.

This method of transferring stitches may be 40 repeated in accordance with requirements by suitably adjusting the aforesaid control mechanism so that by this arrangement a panel effected at the back of a stocking for example is produced, which is identical with the panel produced upon the known type of straight or flat knitting machines, as aforesaid.

45 The heel tabs are made as usual between the knitting of the leg and foot. The operating butts of the needle jacks corresponding to the instep needles or of the instep needles are short, whilst those corresponding to the heel tabs are long. 50 The cam blocks are withdrawn part way till they operate only the long butt jacks for the heel tab needles. As the yarn fingers move from one heel tab to the other in the above-mentioned reciprocatory manner, the two yarn fingers are alternated so that one yarn finger feeds to one tab and the other finger to the other tab. Takeups 55 control the surplus yarn. After the heel tabs are knit, the alternation of the yarn fingers is stopped and the cam blocks move into contact with the short butt needle jacks, and the foot is knit. The toe can be narrowed in the same general manner as the leg.

It will be evident that various alterations, modifications and/or additions may be introduced into 65 the aforesaid construction and arrangement of parts without departing from the spirit and scope of the invention.

What I claim is:

1. A circular machine for knitting one or more 70 fashioned blanks, said machine comprising a stationary needle cylinder, independent needles therein arranged in one or more groups, operating butts at two levels for said needles, a reciprocating yarn carrier for each needle group and 75 cams rotating in opposite directions adapted to

act on the butts at different levels to cause the needles to knit in succession, in combination with narrowing mechanism and means adapted to stop the effective operation of the two cams while the narrowing mechanism is in action. 5

2. A circular knitting machine for knitting one or more fashioned blanks having selvage edges, said machine comprising a stationary needle cylinder, independent needles therein arranged in one or more groups, jack means associated with 10 the needles for operating same and provided with butts at two levels, and two cams rotating in opposite directions operating on the butts at different levels, in combination with narrowing mechanism and means adapted to stop the effective 15 operation of the two cams while the narrowing mechanism is in action.

3. A circular machine for knitting one or more stocking blanks, said machine comprising a stationary needle cylinder, independent needles 20 therein arranged in one or more groups, operating butts at two levels for each of said needles, a reciprocating yarn carrier for each needle group and cams rotating in opposite directions 25 acting on the butts at different levels, each causing all the needles to knit in succession, in combination with means adapted to narrow the blanks by operation of a plurality of points in unison.

4. A circular knitting machine for knitting 30 one or more stocking blanks having selvage edges, said machine comprising a stationary needle cylinder, needles therein arranged in one or more groups, there being a space between the ends of the group or groups, and means associated with the needles and providing operating butts at two levels, in combination with two knitting cam blocks rotating in opposite directions operating on the jack butts at different levels and so timed as to pass each other at the space 40 between the ends of the needle group or groups, narrowing mechanism for said needles and means adapted to stop the knitting operation of the cam blocks while the machine is transferring loops for narrowing. 45

5. A circular machine for knitting one or more stocking blanks having selvage edges, said machine comprising a stationary needle cylinder, independent needles therein arranged in one or more groups whose ends are spaced from each other, multiple operating butts associated with 50 said needles, and cam blocks each acting successively on the operating butts at its own level in the opposite direction to the other, in combination with narrowing mechanism for the 55 needles in each group adapted to cause narrowing over one needle on a plurality of needles simultaneously.

6. A circular machine for knitting a plurality of stocking blanks having selvage edges, said machine comprising a stationary needle cylinder, independent needles therein arranged in a plurality of groups spaced from each other, multiple operating butts associated with each needle and two cam blocks rotating in opposite directions 65 at different levels each adapted to cause all the needles to knit in succession, in combination with narrowing mechanism for each group of needles adapted to manipulate a plurality of needles in unison for transferring stitches and 70 means to halt the effective operation of the cam blocks during the narrowing operation.

7. A circular machine for knitting a plurality of full fashioned stocking leg blanks, said machine comprising a stationary needle cylinder, 75

independent needles arranged therein in a plurality of groups spaced from each other, operating butts at two levels for each of said needles, cams rotating in opposite directions and acting on the butts at different levels, each adapted to cause all the needles to knit in succession, and a reciprocating yarn carrier for each needle group, in combination with unitary cam means adapted to throw the narrowing mechanism and the knitting cams into and out of effective operation in repeated alternation.

8. A circular machine for knitting a plurality of stocking blanks including heel tabs, comprising a stationary needle cylinder, independent needles therein arranged in a plurality of groups spaced from each other, operating butts at two levels for said needles, a reciprocating yarn carrier for each needle group, and cams rotating in opposite directions acting on the butts at different levels, each adapted to cause all the needles to knit in succession, in combination with a plurality of yarn fingers in each carrier, means adapted to change yarn fingers at each oscillation, and means adapted to retract the knitting cams out of the path of the short operating butts, said short butts being associated with the portion of the stocking blanks between the heel tabs.

9. A circular machine for knitting a plurality of stocking blanks having selvage edges, said machine comprising a stationary needle cylinder, independent needles therein arranged in a plurality of groups spaced from each other, jacks for operating said needles each having two or more operating butts, and cam blocks rotating in opposite directions each acting successively on the operating butts at its own level, in combination with narrowing mechanism for the needles in each group having a unitary member adapted to manipulate a plurality of needles en masse for the purpose of transferring stitches.

10. A circular machine for knitting a plurality of stocking blanks having selvage edges, said machine comprising a stationary needle cylinder, independent needles therein arranged in a plurality of groups spaced from each other, multiple operating butts associated with each needle and two cam blocks rotating in opposite directions at different levels each adapted to cause all the needles to knit in succession, in combination with a plurality of narrowing jaw units each adapted to manipulate a plurality of needles in unison for a narrowing operation.

11. A circular knitting machine for knitting a plurality of stocking blanks having selvage edges, said machine comprising a stationary needle cylinder, independent needles therein arranged in a plurality of groups spaced from each other, multiple operating butts associated with each needle and two cam blocks rotating in opposite directions at different levels each adapted to cause all the needles to knit in succession, in combination with narrowing mechanism for each group of needles adapted to manipulate a plurality of needles in unison for transferring stitches and means to halt the cam blocks in the spaces between the needle group during the narrowing operation.

12. A circular machine for knitting a plurality of stocking blanks having selvage edges, said machine comprising a stationary needle cylinder, independent needles therein arranged in a plurality of groups spaced from each other, multiple operating butts associated with each needle and two cam blocks rotating in opposite directions at different levels each adapted to cause all the

needles to knit in succession, in combination with a plurality of narrowing jaw units each adapted to manipulate a plurality of needles in unison for a narrowing operation, each jaw unit comprising a lower jaw and an upper jaw being laterally pivoted and spring-pressed so that the lower jaw can move in under a butt before the upper jaw is above it to enable the jaw to measure and take a new group of needles automatically at each narrowing operation.

13. In a method of manipulating an independent needle stationary cylinder circular knitting machine to make flat stocking blanks where the needles are arranged in a plurality of spaced groups each corresponding to one blank, the steps of knitting on all the needles in succession by means of a cam block rotating in one direction and simultaneously knitting on all the needles in succession in the other direction by means of another cam block rotating at another level, the two blocks passing in a space between the needle groups, and subsequently halting the blocks at such a space while manipulating a plurality of adjacent needles in unison to produce narrowing.

14. In a method of manipulating an independent needle stationary cylinder circular knitting machine to make flat stocking blanks where the needles are arranged in a plurality of spaced groups each corresponding to one blank, the steps of knitting on all the needles in succession by means of a cam block rotating in one direction and simultaneously knitting on all the needles in succession in the other direction by means of another cam block rotating at another level, the two blocks passing in a space between the needle groups, there being a reciprocating yarn feed for each blank, said two cam blocks being driven from a single clutch, and subsequently halting the cam blocks in such space by opening the clutch, and simultaneously engaging another clutch to manipulate a plurality of adjacent needles and points in unison to produce narrowing of a plurality of loops.

15. A circular machine for knitting a plurality of stocking blanks having selvage edges, said machine comprising a stationary needle cylinder, independent needles therein arranged in a plurality of groups spaced from each other, multiple operating butts associated with each needle and two cam blocks rotating in opposite directions at different levels each adapted to cause all the needles to knit in succession, a plurality of units each adapted to move a plurality of knitting elements vertically in unison for a narrowing operation, each unit having two jaws adapted to lie above and below butts on the knitting elements, the upper jaw being laterally pivoted and spring-pressed whereby the unit can depress a group of knitting elements to idle position, move laterally and rise leaving part of the group in idle position and taking butts of one or more additional elements at a higher level into the unit, and means to halt the cam blocks in the spaces between the needle groups during the narrowing operation.

16. In a method of manipulating an independent needle stationary cylinder circular knitting machine to make flat stocking blanks where the needles are arranged in a plurality of spaced groups each corresponding to one blank, the steps of knitting on all the needles in succession by means of a cam block rotating in one direction and simultaneously knitting on all the needles in succession in the other direction by means of another cam block rotating at another level, the two

blocks passing in a space between the needle groups, while reciprocating separate yarn guides for each group of needles and halting the blocks at such a space and lowering a group of needles to idle position by means of jaws above and below butts for said needles, moving laterally the jaw

below the butts to a position below a different group of butts, raising the jaws to the level of adjacent butts and then moving the upper jaw laterally into register with the lower jaw and subsequently resuming knitting.

5

ARTHUR PASS.
